UNITED STATES PATENT OFFICE.

HERBERT L. SMITH, OF CLINTON, MASSACHUSETTS, ASSIGNOR TO CLINTON WIRE CLOTH COMPANY, OF BOSTON, MASSACHUSETTS, A CORPORATION OF MASSACHUSETTS.

CRIMPING APPARATUS FOR ELECTRIC WELDING-MACHINES.

No. 896,476.

Specification of Letters Patent. Patented Aug. 18, 1908.

Application filed September 9, 1907. Serial No. 391,889.

To all whom it may concern:

Be it known that I, HERBERT L. SMITH, of Clinton, in the county of Worcester and State of Massachusetts, have invented certain new and useful Improvements in Crimping Apparatus for Electric Welding - Machines, of which the following is a specification.

This invention relates to a new and improved crimping apparatus for electric welding machines for welding wire fabrics.

Figure 1 in side elevation shows a construction made in accordance with my invention, a part of the center of the girth being broken away. Fig. 2 is a cross-sectional view taken on line 2—2 of Fig. 1, looking in the direction of the arrow. Fig. 3 is a cross-sectional view on line 3—3 of Fig. 2.

The same letters of reference indicate the same parts in all of the figures.

In machines of this general class it is frequently found desirable to crimp the strand wire; in other words, to form bends in said wire, either for purposes of ornamentation or for purposes of utility, in order to provide a yielding capacity in the fabric. In the use of such crimping devices, it is necessary to have the crimping-jaws accurately located, in order to crimp the strand wires between the stay wires at the proper point. The stay wires are applied to the strand wires at different distances in different classes of goods, so that some provision is necessary to readily and accurately change the crimping-jaws to correspond with any selected position for the stay wires. By my invention, the above described result is secured by an efficient and simple mechanism.

1, 1, represent parts of side members of the frame of a machine for electrically welding wire fabric, such as for instance, is shown in United States patent to Perry, No. 813,823, granted February 27, 1906.

My invention relates only to one detail of that machine, and the main part of the machine need not, therefore, be described.

3 represents a girth, each end of which is formed with flanges 4, 4, which extend out

beyond each side of the girth. In each flange 4 is formed a slot 5. A bolt 6 is arranged in each slot 5, the head of the bolt engaging the flange 4, the end of the bolt being tapped into the girth. By this means each end of the girth is connected with the frame 1, by means of the slots 5 and bolts 6, which permits the ends of the girth to be adjusted up and down by means hereinafter described, and thereafter locked in adjusted position by tightening the bolts 6.

7 represents a screw-threaded hub formed in the flange 4 on each end of the girth. In each screw-threaded hub is arranged a complementary screw-threaded rod 8. The upper end of each rod is arranged in a hub 9 of the framework and secured in position by a nut 10. The lower end of each rod extends through a complementary hub 11 below the girth.

12 represents a hand wheel secured to the lower end of each rod 8 below the hub 11, it being understood that the rod 8 is not provided with screw-threads at the point where it engages the hubs 9 and 11, but is free to turn therein. By loosening the bolts 6 and turning the hand wheels 12 the ends of the girth may be adjusted up or down, in order to bring the crimping members in the right position with respect to the fabric being made. Thereafter, the bolts 6 are tightened, thus rigidly securing the ends of the girth to the framework 1, and relieving the screw-threads of the bolts 8, from strain.

Upon the girth as shown, there are arranged a series of stationary crimping jaws 14, a series of movable crimping jaws 15 carried by the slide 16, the said slide being operated by a cam 18, as set out in the before-mentioned patent to Perry, No. 813,823.

Having thus explained the nature of my invention and described a way of constructing and using the same, though without attempting to set forth all of the forms in which it may be made, or all of the modes of its use, what I claim and desire to secure by Letters Patent is:—

In a machine for making welded wire fab-

ric organized with a suitable framework, a girth formed upon each end with a flange, a slot formed on each flange on each side of said girth, a bolt arranged in each slot and 5 positioned in the framework, an adjusting screw mounted in each end of said girth and suitably connected to the framework, and means for operating said screws whereby the ends of said girth may be positioned at any

desired point and thereafter locked in position by said bolts.

In testimony whereof I have affixed my signature, in presence of two witnesses.

HERBERT L. SMITH.

Witnesses.
